UNITED STATES PATENT OFFICE

2,002,258

METHOD OF PRODUCING TUBING

Sylvester F. Clement, Chicago, Ill., assignor to
The Visking Corporation, Chicago, Ill., a corporation of Virginia

Application April 9, 1934, Serial No. 719,783

2 Claims. (Cl. 18—57)

The invention relates to a method of producing tubing and more particularly to a method of producing seamless cellulose tubing.

In practice, seamless cellulose tubing is generally manufactured by extruding viscose through an annular orifice into coagulating and regenerating baths, after which the tubing is washed in water and treated with a softening agent. The several baths are held in tanks or receptacles and rollers are provided for advancing the tubing through the baths, the tubing being preferably produced continuously over a period of days and even months. Gases are evolved in the tubing during the coagulating and regenerating steps and it is necessary to effect the escape of the gases from the tubing. This may be done by puncturing the tubing at intervals.

As set forth in my Patent 1,958,181 the tubing tends to wrinkle or fold as it passes over the rollers. Such wrinkling or folding of the tubing renders it unfit for commercial purposes.

An object of the present invention is to provide an improved method for insuring that the gases evolved in the tubing during the coagulating and regenerating steps will be discharged therefrom and that the tubing will be retained in an unfolded and unwrinkled condition when it is punctured to permit the escape of the gases.

In the accompanying drawing Fig. 1 is a somewhat diagrammatic longitudinal section taken through apparatus for producing seamless cellulose tubing.

Fig. 2 is a plan view of the apparatus shown in Fig. 1.

Fig. 3 is an enlarged fragmentary view of a section of seamless tubing which has been punctured to permit escape of gases evolved therein, means being shown for holding the tubing in an unwrinkled condition.

Fig. 4 is a side view of the section of tubing shown in Fig. 3.

Fig. 5 is a fragmentary elevation of a section of tubing which has been punctured to permit escape of the gases evolved therein, and

Fig. 6 is a section taken on line 6—6 of Fig. 5.

Referring for the present to Fig. 1 of the drawing wherein apparatus for producing seamless cellulose tubing is illustrated, the reference character 10 designates generally apparatus for extruding viscose through an annular orifice 11 into a coagulating or regenerating bath 12 which is held in a receptacle 13. The tubing thus formed is advanced over a roller 14 to a series of rollers 15 and 16. The rollers 15 are disposed

above a plurality of tanks 18, the rollers 16 being immersed in baths held in the tanks 18. The baths may be regenerating baths. It will be noted that the tubing 20 is trained over the rollers 15 and 16 in such manner that the tubing passes through the baths held in the tanks 18.

As illustrated in Fig. 2, a plurality of extruding devices 10 are employed in connection with a single bath 12 so that a plurality of tubes 20 are continuously being formed and advanced over the rollers 14, 15 and 16.

During the passage of the tubes 20 through the bath 12 and the baths held in the tanks 18 gases are evolved within the tubing. These gases distend the tubing and the tubing must be punctured at intervals to permit the escape of the gases.

At predetermined intervals, the operator cuts a slit 25 in the tubing 20 as it is being advanced (Fig. 3). The operator then places a metallic clip 26 over the tubing directly beneath (behind) the slit 25. The clip 26 is preferably formed from wire and is adapted to hold the tubing in a flat, collapsed condition. The direction in which the tubing is advancing is indicated by the arrow 28 in Fig. 3. Obviously, gas evolved in the tubing 20 in advance of the slit 25 will escape through the slit 25 as the tubing continues to pass around the rollers 14, 15 and 16. The clip 26 prevents the gas in the tubing in advance of it from passing into that section of the tubing disposed between the clip 26 and the extruding orifice 11.

The clip 26 insures that the tubing will remain in a flat, unwrinkled condition as it passes through succeeding baths.

In Figs. 5 and 6, another form of clip is shown in place of the clip 26. In Figs. 5 and 6 the tubing 20 is held flattened beneath the slit 25 by two sticks 30 which have their ends secured to each other by rubber bands 31. These sticks 30 are described in my co-pending application identified above. The sticks 30 are preferably flat pieces of wood notched at the ends to receive the rubber bands 31. It is obvious that after a slit 25 has been cut in the tubing 20, the operator may attach the sticks 30 directly beneath the slit 25 to insure that the tubing will remain in a flat, unwrinkled condition and to insure that the gas in advance of the slit 25 will not pass to that section of tubing disposed between the slit and the extruding orifice 11.

While I have shown and described certain embodiments of my invention, it is to be understood that it is capable of many modifications.

Changes, therefore, in the construction and arrangement may be made without departing from the spirit and scope of the invention as disclosed in the appended claims, in which it is my intention to claim all novelty inherent in my invention as broadly as possible, in view of the prior art.

I claim:

- 10 1. A method of making cellulose tubing which comprises: extruding viscose through an annular orifice into a coagulating bath, thereby forming a seamless tube; carrying the tube on rollers through a subsequent regenerating bath, or baths; and making slits in the tube at intervals 15 and flattening and clamping the tube in flattened

condition sufficiently close to the slits to prevent the tube from gaping open or wrinkling at the slit, the slits being left in open condition.

- 5 2. A method of making cellulose tubing which comprises: extruding viscose through an annular orifice into a coagulating bath, thereby forming a seamless tube; carrying the tube on rollers through a subsequent regenerating bath, or baths; and making slits in the tube at intervals and flattening and clamping the tube in flattened 10 condition back of and sufficiently close to prevent the tube from gaping open or wrinkling at the slits, the slits being left in open condition.

SYLVESTER F. CLEMENT.
